REDUCTION IN Pu RECOVERY PROCESSES

David M. Ritter, Seattle, and Robert P. S. Black, Richland, Wash., assignors to the United States of America as represented by the United States Atomic Energy Commission

No Drawing. Application December 21, 1945
Serial No. 636,494

2 Claims. (Cl. 23—14.5)

This invention relates to a procedure for processing materials containing the element of atomic number 94, known as plutonium, for separating the plutonium from extraneous matter such as substances of the kind present in neutron irradiated uranium as exemplified by uranium and especially fission products, and the like radioactive contaminants. More particularly, this invention concerns a separatory and concentration procedure employing a combination of carriers and involving the use of an oxalate reagent wherein improved reduction and carrying are obtained.

As described herein, the isotope of element 94 having a mass of 239 is referred to as $^{94}\text{Pu}^{239}$ and is also called plutonium, symbol Pu. In addition, the isotope of element 93 having a mass of 239 is referred to as $^{93}\text{Pu}^{239}$. Reference herein to any of the elements is to be understood as denoting the element generically, whether in its free state or in the form of a compound, unless indicated otherwise by the context.

Elements 93 and 94 may be obtained from uranium by various processes which do not form a part of the present invention including irradiation of uranium with neutrons from any suitable neutron source, but preferably the neutrons used are obtained from a chain reaction of neutrons with uranium.

Naturally occurring uranium contains a major portion of $^{92}\text{U}^{238}$, a minor portion of $^{92}\text{U}^{235}$, and small amounts of other substances such as UX_1 and UX_2 . When a mass of such uranium is subjected to neutron irradiation, particularly with neutrons of resonance or thermal energies, $^{92}\text{U}^{238}$ by capture of a neutron becomes $^{92}\text{U}^{239}$ which has a half life of about 23 minutes and by beta decay becomes $^{93}\text{Pu}^{239}$. The $^{93}\text{Pu}^{239}$ has a half life of about 2.3 days and by beta decay becomes $^{94}\text{Pu}^{239}$. Thus, neutron irradiated uranium contains both $^{93}\text{Pu}^{239}$ and $^{94}\text{Pu}^{239}$ but by storing such irradiated uranium for a suitable period of time, the $^{93}\text{Pu}^{239}$ is converted almost entirely to $^{94}\text{Pu}^{239}$.

In addition to the above-mentioned reaction, the reaction of neutrons with fissionable nuclei such as the nucleus of ^{235}U results in the production of a large number of radioactive fission products. As it is undesirable to produce a large concentration of these fission products which must, in view of their high radio-activity, be separated from the $^{94}\text{Pu}^{239}$ and further as the weight of radioactive fission products present in neutron irradiated uranium is proportional to the amounts of $^{93}\text{Pu}^{239}$ and $^{94}\text{Pu}^{239}$ formed therein, it is preferable to discontinue the irradiation of the uranium by neutrons when the combined amount of $^{93}\text{Pu}^{239}$ and $^{94}\text{Pu}^{239}$ is equal to approximately 0.02 percent by weight of the uranium mass. At this concentration of these substances, the concentration of fission elements which must be removed is approximately the same percentage.

A number of processes have already been proposed for accomplishing the separation and concentration of Pu. Certain of these processes are generically known as the "bismuth phosphate" type process and the "wet fluoride" type of process. These processes are the invention

2

of others and the details of the processes are described in copending applications, as for example, application Ser. No. 519,714 of Thompson and Seaborg, now U.S. Patent 2,785,951, to be referred to hereinafter, which gives details relative to the aforementioned processes. Consequently, all of the details of operation of the aforementioned processes are not described herein.

In one type of procedure in successful use it is customary to utilize both the bismuth phosphate treatment and a lanthanum fluoride treatment. Consequently, both types of treatment are referred to herein for background although the present invention is concerned particularly with intermediate phases of the procedures which in some instances may be considered as associated with the former and other instances associated with the latter type process. That is, for example, the present invention concerns the treatment of a solution containing Pu in a higher valence state as exemplified by a nitric acid solution containing $\text{Pu}^{(o)}$ from a lanthanum fluoride or bismuth phosphate precipitation, or other similar solutions containing $\text{Pu}^{(o)}$. In processes of the aforementioned type, either combination processes where several different types of carriers are used or processes in which the same carrier is used at various points in the process it is necessary to change the $\text{Pu}^{(o)}$ to $\text{Pu}^{(r)}$ for reasons to be set forth in greater detail hereinafter. It has already been proposed in existing processes to use hydrogen peroxide, various ferrous compounds or the like for this purpose. While such reagents function to convert the $\text{Pu}^{(o)}$ to $\text{Pu}^{(r)}$, it has been found that by the reagents of the present invention, as exemplified by oxalic acid, the conversion of $\text{Pu}^{(o)}$ to $\text{Pu}^{(r)}$ is better accomplished and other steps of the process are improved in that at least as high or better recovery of Pu may be obtained while in certain instances employing smaller concentrations of some of the reagents for forming the carrier precipitates in the subsequent steps.

That is, by the present invention carried out in conjunction with steps such as the BiPO_4 and LaF_3 carrying which have been previously worked out, but altered in accordance with the present invention in the reduction phase the advantage of improved reaction may be obtained as will be described.

The meaning of the terms bismuth phosphate type of process, wet fluoride type of process, reduction, $\text{Pu}^{(o)}$, $\text{Pu}^{(r)}$, product precipitate, and similar terms will be apparent as the description proceeds.

This invention has for one object, to provide improvements in methods for the separation and recovery of plutonium.

Another object is to provide a method of separating plutonium characterized by certain steps in which different reagents and procedure than have heretofore been used are employed.

Still another object is to provide an improved procedure for converting $\text{Pu}^{(o)}$ to $\text{Pu}^{(r)}$.

Still another object is to provide a procedure for treating solutions containing $\text{Pu}^{(o)}$.

A still further object is to provide a process for the reduction of solutions carrying $\text{Pu}^{(o)}$ resulting from LaF_3 or BiPO_4 by-product precipitation, which may be used in place of or in conjunction with usual reduction.

Still another object is to provide a new and improved reduction operation which lends itself to the use of and to coupling with steps already known or practiced for the separation and recovery of Pu.

Another object is to provide a process for converting $\text{Pu}^{(o)}$ to $\text{Pu}^{(r)}$ which may employ some of the materials used in existing processes and which may be carried out in existing equipment without change, or with little equipment change.

Still another object is to provide a process for the reduction treatment of solutions containing Pu either in relatively small or large amounts.

Other objects will appear hereinafter.

As already indicated, it has been found that Pu in admixture with various extraneous material may be separated and concentrated by the use of a series of steps involving oxidation and reduction and the utilization of carrier precipitates such as BiPO_4 and LaF_3 . These treatments are in accordance with known practice. However, we have found that the formation of, for example, a LaF_3 carrier precipitate may be rendered simpler and more efficient by interposing the reduction type procedure described herein such as the use of a different type of reagent and other variations such as the use of less HF in forming the carrier. By the utilization of these features, not only are the advantages previously obtained in the processes still obtainable, but further advantages are obtained such as better carrying of Pu and less corrosion.

Illustrations of the types of carrier precipitates which may be formed are described in U.S. Patent 2,785,951 of Thompson and Seaborg, aforementioned, and reference is made to that patent for further disclosure, details thereof being omitted from the present disclosure except where necessary to an understanding of the present invention. As set forth in said application, it has been discovered that plutonium has more than one oxidation state, including a lower oxidation state or states herein referred to as $\text{Pu}^{(r)}$ in which the element is characterized, for example, by forming insoluble phosphates and fluorides and a higher oxidation state or states referred to as $\text{Pu}^{(o)}$ in which the element forms soluble phosphates and fluorides.

When a carrier precipitate is formed in a solution containing $\text{Pu}^{(o)}$ such precipitate is referred to as a by-product precipitate since it carries down fission products and other extraneous material. When the carrier precipitate is formed in a solution containing $\text{Pu}^{(r)}$, this precipitate is referred to as a product precipitate since the plutonium $\text{Pu}^{(r)}$ is a component primarily carried. The precipitation and other steps in the process of the present invention will be carried out much the same as existing procedures. That is, irradiated material from which Pu is to be recovered is treated by an existing or standard process for eliminating at least a part of the extraneous matter. At some point in the process a solution is obtained containing $\text{Pu}^{(o)}$ from which a by-product precipitate has been separated. This solution containing $\text{Pu}^{(o)}$ is then treated in accordance with the present invention with a source of oxalate ion for converting the $\text{Pu}^{(o)}$ to $\text{Pu}^{(r)}$. Then further product precipitation treatments are applied much the same as in existing procedure excepting that smaller quantities of reagents may be used in forming the precipitates. That is, for example, if a lanthanum fluoride product precipitate is formed after the treatment of the present invention, it may be satisfactorily formed with a lower concentration of HF or other source of fluoride ion than hitherto considered necessary.

A further general understanding of the application of our process in the field of separation and recovery of Pu may be had from the following: A suitable source of materials containing Pu is obtained. This source may be the same as described in U.S. Patent 2,785,951 aforementioned and is exemplified by a nitric acid solution known as a UNH (uranyl nitrate hexahydrate) solution which has resulted from and has preferably been subjected to preliminary treatments exemplified by extraction and decontamination by the bismuth phosphate method. The solution may be oxidized and subjected to a standard fluoride by-product precipitation step for eliminating fission products and other undesired components. The oxidized solution containing $\text{Pu}^{(o)}$ may then be treated in accordance with the pres-

ent invention. From the resulting solution containing $\text{Pu}^{(r)}$, a lanthanum fluoride product precipitate formed with the usual or smaller HF additions carries the Pu substantially completely. The preceding general description may be enlarged upon in various respects. If the irradiated material has been enclosed in casings, the casings may be removed in any suitable manner. That is, for example, dissolve the aluminum casings from the metal which has undergone a chain reaction involving fission. Then dissolve the metal slugs from which the casings have been removed in the preceding step. In other words any steps for placing the materials in a better condition for handling and processing may be applied.

The solution resulting from the preceding steps may be reduced by any of the several reducing procedures described such as by incorporating a peroxide, or ferrous compounds or by the present invention. A bismuth phosphate precipitation procedure is then carried out on the solution in the (r) state.

The product precipitate obtained is dissolved and the resultant solution oxidized and otherwise treated in accordance with the usual bismuth phosphate by-product precipitation procedure under (o) conditions to obtain a by-product precipitate which is subjected to centrifuging or other separatory procedure. The solution from the separation step contains the Pu in the (o) state.

At this point the solution containing Pu in the (o) state may be given a LaF_3 by-product precipitation and then reduced and subjected to lanthanum fluoride cycles as described in detail in the pending applications aforementioned. At these points, the use of agents such as hydrogen peroxide or ferrous compounds have heretofore been employed.

In accordance with our improvement such solutions containing $\text{Pu}^{(o)}$ are reduced with oxalic acid. For example, a 0.05 to .125 M solution of oxalic acid added to the solution to be reduced and the reaction maintained for approximately one hour at 75° C. gives satisfactory reduction. The strength of the oxalic acid may vary, for example, from about .022 to .15 M oxalic acid, a particularly useful range being between about .04 and .05 M.

After the reduction treatment, a product precipitation by means of lanthanum fluoride or other desired treatment applicable to a solution containing $\text{Pu}^{(r)}$ may be applied. It has been found that by the use of the oxalic acid recoveries of Pu are better. Also, in general, lower concentrations of HF or other reagent are required in the lanthanum fluoride formation which reduces corrosion.

The invention is further illustrated by the several examples which follow.

Example I

For the purpose of control and comparison, this first example is in accordance with existing procedure. That is, this example shows the use of peroxide, one of the reagents heretofore used for reduction, at a step in a process where it is proposed that the oxalate reducing medium of the present invention be utilized.

Two liters of oxidized product solution from which a BiPO_4 by-product precipitate had been precipitated were used. This contained a total of 14,750 c./m. (counts/minute) of Pu. The solution was made 0.2 N in HF, a lower amount than heretofore usually used, and then reduced with 1% H_2O_2 for two hours at 35° C.

A product precipitate was made by the addition of 225 mg./l. of lanthanum ammonium nitrate. The precipitate carrying Pu was then digested for an additional hour followed by centrifugation in 100 ml. lusteroids. The precipitate was washed into a single lusteroid and studied. The waste liquor was analyzed and the yield figured on this basis.

The exact manner of studying or analyzing the solutions is not a limitation on the present invention and any

procedure applicable to radioactive substances may be employed. For example, by taking the alpha count on the starting solution the amount of Pu present may be determined. Likewise by a count on the waste liquor the amount of Pu remaining may be determined. From the foregoing, the percentage of Pu carried may be arrived at. In Example I, the value was approximately 64.6% carried.

In the next example the same type solution was treated by similar procedure excepting that the procedure of the present invention was utilized as will be apparent from the example.

Example II

Approximately 2,000 ml. of oxidized product solution from which a BiPO₄ by-product precipitate had been precipitated were used. This solution contained a total of 14,750 c./m. of Pu.

The solution was reduced by the addition of 31.5 grams of solid H₂C₂O₄·2H₂O. This made the solution 0.125 M therein. The solution was heated to 75° C. and held for 1 hour followed by cooling to room temperature. 225 mg./l. of La⁺⁺⁺ was then added followed by the dropwise addition of HF over a 30 minute period to make the solution 0.2 N in HF. This was then digested for 60 minutes, centrifuged in 100 ml. lusteroids and the precipitate gathered, washed and studied as above. The mother liquor was analyzed and the yield figure based on this analysis. In this example, even though the conditions of .2 N in HF were used, the yield was 99.24%.

Example III

Another run, in accordance with the present invention, was carried out on 180 ml. of a 10 N, 2 cycle BiPO₄ solution as a starting material. This solution was made 5 N in HNO₃ and oxidized for one hour at 50° C. with 0.01 M NaBiO₃. The BiPO₄ was precipitated by diluting to 1 N HNO₃ and the resultant precipitate was digested for 1/2 hour, filtered, and washed with 100 ml. of 1 N HNO₃-0.1 M H₃PO₄. The volume was now 1900 ml.

Reduction was accomplished by the use of H₂C₂O₄ of 0.125 M at 75° C. for one hour. The solution was then cooled and 225 mg./l. of La⁺⁺⁺ added. The precipitation was accomplished by the addition of HF slowly over a period of 1/2 hour to make the solution .2 N therein. The precipitate was then digested for one hour, centrifuged in 100 ml. lusteroids, the precipitate aggregated and studied. The yield was based on the loss in the final mother liquor as in the preceding examples, and was found to be greater than 98%.

Since from the several examples there was evidence that H₂C₂O₄ reduced advantageously further runs were carried out to establish conditions for its use and to evaluate subsequent product carrying. These further runs showed that Pu is satisfactorily reduced by 0.05-0.125 M oxalic acid (1 hour at 75° C.) and that no difficulty is experienced in carrying with LaF₃ in 0.2-0.5 N HF after its use.

In two runs 0.125 M H₂C₂O₄ was used and the reduced product was carried from 0.2 N HF by co-formed LaF₃. Since the precipitate was intended for metathesis studies, the efficiency of reduction and carrying was based on alpha analysis of the reduced waste liquor. In two subsequent runs, reduction was carried out with 0.05 M H₂C₂O₄ and efficiency was determined by analysis of the reduced product solution as well as analysis of the product precipitate and reduced waste liquor. Lanthanum fluoride was co-formed in 0.2 N HF and in 0.5 N HF.

The results of these various runs indicated that substantially complete reduction in an HF-free system can be obtained by means of H₂C₂O₄ over the preferred range of 0.05 M to 0.125 M and that subsequent co-formed precipitation of LaF₃ affords substantially complete recovery of Pu at the lower HF concentrations of 0.2 N to 0.5 N.

For the preliminary runs the starting solution was a 10 N HNO₃ solution of BiPO₄ product of a plant type. A BiPO₄ by-product precipitation was made and the oxidized product solution was reduced with H₂C₂O₄, using a 1-hour digestion at 75° C. Concentrations during reduction were 0.1 M H₃PO₄, 1 M HNO₃, and 0.125 M H₂C₂O₄. At room temperature, 225 mg. per liter of La⁺⁺⁺ was added to the reduced solution, concentrated HF was added slowly over 30 minutes to obtain a concentration of 0.2 N HF, and the precipitate was separated after 60 minutes of agitation. The results, based on alpha analyses of the waste liquors, are summarized in the following table:

	Run 1	Run 2
Total starting count (c./m.)	14,540	11,330
Reduced count in waste (c./m.)	106	120
Total count in waste (c./m.) (after reduction with SO ₂)	119	163
Percent reduction	99.9	99.6
Percent carrying	99.3	98.9

A second product solution in 10 N HNO₃ (approximate alpha count 790 c./ml.) was used for the subsequent runs. After a standard BiPO₄ by-product precipitation, the oxidized product solution was reduced with H₂C₂O₄ in 25-12 stainless steel, using a 1-hour digestion at 75° C. Concentrations during reduction were 0.1 M H₃PO₄, 1 M HNO₃, and 0.05 M H₂C₂O₄. The efficiency of the reduction is indicated by the data given in the following table:

Total starting count (c./m./ml.)	76.8
Reduced count in product solution (c./m./ml.)	75.0
Percent reduction	97.7

Aliquots of this reduced solution were used to test product carrying by LaF₃ co-formed in 25-12 stainless steel at room temperature. To the aliquot was added 225 mg. per liter of La⁺⁺⁺, after which 27 N HF was added slowly over a 30-minute period, with good mechanical agitation. After stirring for 90 minutes, the precipitate was separated, fumed with H₂SO₄ to remove fluorides, taken up in HNO₃, and analyzed. The waste liquor was analyzed by the preforming procedure. The following table summarizes the results of the precipitation step:

	0.2 N HF	0.5 N HF
Total starting count (c./m./ml.)	76.8	76.8
Precipitate analysis (c./m./ml.)	75.8	74.3
Waste liquor analysis (c./m./ml.)	0.1	0.1
Percent recovery	98.7	96.7
Percent material balance	98.8	96.8

By a co-formed precipitate is meant the formation of the precipitate in accordance with the procedure given in certain of the examples. That is, a co-formed precipitate is produced by an operation described as a hydrogen fluoride strike. A source of lanthanum ions is first incorporated in the solution in which the carrier is to be formed. Thereafter, the source of fluoride ions, such as the addition of hydrogen fluoride, is made to cause the formation of the lanthanum fluoride precipitate. While certain procedure has been described in the preceding examples, the exact manner of forming the precipitates is not a limitation on our invention.

The present invention relative to the use of oxalate reduction may be used when the carrier precipitates are formed by other procedures for example in conjunction with the formation of a preformed precipitate. A preformed precipitate is produced by incorporating a source of, for example, fluoride ions such as excess hydrogen fluoride into the solution containing Pu in which the carrier precipitate is to be formed. Thereafter, a source of lanthanum ions is added to the solution. In other words, a preformed precipitate, a conventional type of precipitate formation in this art is produced by procedure described as a lanthanum strike.

Likewise, the present invention is not restricted to the use of oxalic acid as the source of the oxalate ion. While such reagent is useful from the standpoint that the oxalate ion is incorporated and at the same time only hydrogen ions incidentally introduced into the solution when the oxalic acid ionizes, various other sources of oxalate ions may be used. Such other sources are exemplified by sodium and potassium oxalates as the incidental introduction of sodium or potassium ions is not detrimental to the process. The mechanism of the reaction has been described herein as reduction since as indicated the valence of the plutonium is changed from a higher to a lower valence. It may be that the oxalate ion aids the process by some other action such as exerting an influence on the formation of complexes or otherwise functions to improve the carrying of the plutonium. Inasmuch as the reactions on the present materials may be complicated and because of the small quantities involved as well as the presence of radioactive materials, the complete mechanism of carrying may in some respects be obscure, and it is not desired to be limited to any theory of operation. For the purpose of description, the treatment herein described as introducing oxalate ions into the process at certain phases thereof will generally be referred to as oxalate reduction. Such terminology is intended to embrace the addition of oxalic acid, sodium oxalate, or various other sources of the oxalate ion or mixtures of such reagents.

It has been shown from the foregoing that in the processes for the recovery and separation of plutonium based on alternate oxidation and reduction stages using a combination of carriers such as bismuth phosphate and lanthanum fluoride, the processes may be improved by interposing the treatment of the present invention comprising oxalate reduction. Not only does the oxalate reduction of the present invention accomplish change of valence state of the plutonium from a higher valence state to a lower valence state, but as shown in the examples, it enables the production of satisfactory carrying by the use of lower concentrations of reagents as exemplified by the use of HF between .2 N and .5 N. Heretofore, concentrations of HF have usually been higher than .5 N and in the present invention such higher contents may also be used if desired but are not required for good results. As indicated in the present examples, the oxalate reduction is preferably carried out at around 75° C., however, various other temperatures may be used within the range of slightly above room temperature to 100° C. It has been found that the utilization of the herein-described invention does not hamper the subsequent treatment of the carrier precipitates by existing practice. For example, the lanthanum fluoride precipitates which are formed in accordance with the present invention using only .2 normal HF may be subjected to metathesis or other comparable procedures and otherwise processed to isolate the Pu therefrom by any of the methods heretofore used. It is therefore apparent that

the present invention may be carried out under various circumstances and in conjunction with various alternate oxidation and reduction processes utilizing the same carrier repeatedly or preferably a combination of carriers as described.

According to the best evidence available, the oxidation state of plutonium secured in solution by the action of the oxidizing agents referred to herein and in cited pending application Ser. No. 519,714, now U.S. Patent No. 2,785,951, is greater than four, and the oxidation state secured in solution by the action of the reducing agents referred to herein and therein is no greater than four. It should therefore be understood that, as used herein, "Pu^(o)" and "Pu in the (o) condition (or state)" are both synonymous with "plutonium in an oxidation state greater than four" and "Pu^(r)" and "Pu in the (r) condition (or state)" are both synonymous with "plutonium in an oxidation state no greater than four."

It is to be understood that all the matter contained in the above description and examples shall be interpreted as illustrative and not limitative of the scope of this invention.

We claim:

1. In processes for the separation and recovery of plutonium values from an aqueous solution containing the same, comprising carrier precipitation of said plutonium values from said solution by means of precipitation therein of bismuth phosphate while maintaining the plutonium in a valence state not above four, derivation from the resulting carrier precipitate of an aqueous acidic solution containing said plutonium values in a valence state greater than four, and thereafter carrier precipitation of said plutonium values from said acidic solution by means of precipitation therein of lanthanum fluoride while maintaining the plutonium in a valence state not above four, the improvement method which comprises the combination with the aforesaid procedure, of reduction of plutonium in a valence state greater than four in said acidic solution to a valence state no greater than four by means of incorporating oxalate ions therein to a concentration within the approximate range of 0.022 to 0.15 molar, prior to said precipitation of lanthanum fluoride therein.

2. The process of claim 1 in which the oxalate ions are incorporated in the form of oxalic acid.
